U.S. Appl. No. 14/170,584, filed Feb. 1, 2014, Van Alen et al.
(Continued)*Primary Examiner* — Mitchell Siegel(74) *Attorney, Agent, or Firm* — Fish & Richardson P.C.(57) **CLAIM**

The ornamental design for an athletic stick head, as shown and described.

DESCRIPTION

FIG. 1 is a top perspective view of a first embodiment of an athletic stick head;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof; and,

FIG. 8 is a bottom perspective view thereof.

The broken line showing is included for the purpose of illustrating and forms no part of the claimed design.

The dotted lines shown in FIGS. 1 and 2 represent the bounds of the claimed design.

1 Claim, 8 Drawing Sheets(56)
